GAS BURNER

John C. Rogers, Cicero, Ill., assignor to Crown
Stove Works, Cicero, Ill., a corporation of
Illinois

Application June 21, 1934, Serial No. 731,690

4 Claims. (Cl. 156—116)

The present invention relates to burners for gas stoves, ranges, and the like, having reference more particularly to burners of the annular type.

A known burner of this type, on which the present improvements are based, consists of a hollow annular body member open at its top and formed with an outer wall having a downwardly flaring smooth outer surface, and a cover plate seated on the outer and inner walls of the body member and detachably secured in place by a central screw, the under side of the outer portion of the cover plate, which has a tapered seat on the outer peripheral wall of the body member, being radially channeled to form a ring of upwardly and outwardly inclined jet ducts.

It is well known by the manufacturers of gas burners that, in order to insure a pure, blue Bunsen flame, an adequate supply of so-called secondary air must be supplied to the flame practically at the base of the flame, the upward flow of the secondary air being induced by the heated air above the burner. And the best results are secured where the stream of secondary air is made to impinge on the flame at a more or less acute angle to the latter.

It is the object of the present invention to improve and make more efficient burners of the type above described, and this is done by a novel construction by which the flow of secondary air to the flame jets, when the burner is lighted, is greater in volume and more efficiently applied.

In the accompanying drawing I have illustrated one practical physical embodiment of the principle of the invention, and referring thereto —

Fig. 1 is a top plan view.

Fig. 2 is a side elevation of the burner proper.

Fig. 3 is a central vertical section through the burner, taken on the line 3—3 of Fig. 1.

Referring to the drawing, 10 designates as an entirety a hollow annular body member open at its top, the outer and inner peripheral walls 11 and 12 of which terminate in inclined seats 13 and 14 respectively that receive a tapered cover plate 15. The body and cover plate are united by a screw 16 that enters a tapered hole 17 in a bridge bar 18 spanning the central hole of the body 10 and is equipped on its upper end with a wing handle 19. Integral with or secured to the body 10 is the usual mixing tube 20 which supplies the gas and primary air to the burner, the tube being equipped at its outer

end with the usual gas cock and air regulating valve (not shown).

The under side of the outer portion of the cover plate 15 which occupies the seat 13 is formed with a ring of radial grooves or channels 21 that form upwardly and outwardly inclined jet ducts at the top of the outer periphery of the burner. It will be observed that the outer peripheral wall 11 has an upwardly flared outer surface, and this surface is formed with a ring of flutes 22 that at their upper ends meet and merge into the outer ends of the jet ducts 21 at an acute angle to the latter. Preferably and as shown each flute is wide enough to span two or three jet ducts.

By reason of this construction, the secondary air, as it rises, hugs the flutes and consequently impinges on the flame jets at their bases at an acute angle thereto, thus preventing any yellow streaks in the flames due to incomplete combustion of the gas, and creating a pure, blue Bunsen flame of intense heat.

Specific details of the structure herein shown and described may be varied within the principle of the invention and without sacrifice of its efficiency for the purposes stated; and hence, I do not limit the invention to the specific structure presented for purposes of illustration, but reserve such modifications and variations as fall within the scope and purview of the appended claims.

I claim:

1. A gas burner, comprising a hollow annular body member open at its top, a cover plate seated on said body member, one of the meeting surfaces of said body member and cover plate being radially channeled to form a ring of jet ducts, and the outer peripheral wall of said body member being formed with upwardly and outwardly inclined flutes merging at their upper ends into the outer ends of said jet ducts, and means for uniting said body member and cover plate.

2. A gas burner, comprising a hollow annular body member open at its top, a cover plate seated on said body member, one of the meeting surfaces of said body member and cover plate being radially channeled to form a ring of upwardly and outwardly inclined jet ducts, and the outer peripheral wall of said body member being formed with upwardly and outwardly inclined flutes each merging into the outer ends of a plurality of said jet ducts, and means for uniting said body member and cover plate.

3. A gas burner, comprising a hollow annular

body member the outer peripheral wall of which is formed with an upwardly flared outer surface, a cover plate seated on said body member, the meeting surfaces of said body member and cover plate being tapered and one of them being radially channeled to form a ring of upwardly and outwardly inclined jet ducts, and the flared surface of said body member being formed with flutes merging at their upper ends at an acute angle into the outer ends of said jet ducts, and means for uniting said body member and cover plate.

4. A gas burner, comprising a hollow annular

body member the outer peripheral wall of which is formed with an upwardly flared outer surface, a cover plate seated on said body member, the meeting surfaces of said body member and cover plate being tapered and one of them being radially channeled to form a ring of upwardly and outwardly inclined jet ducts, and the flared surface of said body member being formed with flutes each merging at its upper end at an acute angle into the outer ends of a plurality of said jet ducts, and means for uniting said body member and cover plate.
